UNITED STATES PATENT OFFICE.

EUGENE S. FOLJAMBE, OF DREXEL HILL, PENNSYLVANIA.

SOUNDING WHEELED TOY.

1,276,747.

Specification of Letters Patent. Patented Aug. 27, 1918.

Application filed January 26, 1917. Serial No. 144,729.

To all whom it may concern:

Be it known that I, EUGENE S. FOLJAMBE, a citizen of the United States, residing at Drexel Hill, in the county of Delaware and 5 State of Pennsylvania, have invented a certain new and useful Sounding Wheeled Toy, of which the following is a specification.

This invention appertains, broadly stated, to toys and relates more particularly to that 10 type of toy known in the art as a hobby-horse.

The principal object of the present invention is to improve that type of toy known in the art as a hobby-horse by providing certain 15 up to date features with the end in view of producing a commercially valuable toy for use by children of tender age or in other words children having a vivid imagination. A further object of the present invention is 20 to provide a toy embracing a simple, compact, durable and comparatively inexpensive construction for affording amusement to children of tender age. Other and further objects of the present invention reside in the 25 providing of a toy embodying certain features, combinations and arrangements of parts as will hereinafter more fully appear.

The invention consists of the improvements hereinafter described and finally 30 claimed.

The nature, characteristic features and scope of the invention will be more fully understood from the following description taken in connection with the accompanying 35 drawings forming part hereof and in which:

Figure 1 is a view in side elevation of a toy embodying features of the invention.

Fig. 2 is a plan view thereof.

Fig. 3 is a fragmentary view partly sectioned of the axle construction.

Fig. 4 is a similar view of the steering post.

Fig. 5 is a view in section taken upon the line 5—5 of Fig. 3.

Fig. 6 is a view in side elevation partly sectioned of a modified form of toy; and

Fig. 7 is a view in front elevation thereof.

For the purpose of illustrating my invention, I have shown in the accompanying 50 drawings one form thereof which is at present preferred by me, since the same has been found in practice to give satisfactory and reliable results, although it is to be understood that the various instrumentalities of 55 which my invention consists can be variously arranged and organized and that my inven-

tion is not limited to the precise arrangement and organization of the instrumentalities as herein shown and described.

In the drawings, as shown in Figs. 1 to 5 60 inclusive, the toy, which in the trade is known as a hobby-auto, is constructed principally of wood and in a very simple and inexpensive manner so as to be sold cheaply. The toy is designed for use by children, for 65 instance, between the ages of two and four years, whose sense of imagination is vivid. In said figures the toy is shown as comprising a structure symbolic of an automobile in which the forward part 10 is representative 70 of a steering post and cranking device, the rear part 11 is representative of a driving axle and "exhaust" and the intermediate part 12 is representative of the body of the machine. In practice, a child with his or her 75 feet upon the ground uses the toy by straddling the part 12 as in using a hobby-horse as is well understood in the art. The forward part 10 consists of a member symbolic of a steering post 13 mounted upon 80 which is a disk 14 hereinafter termed a "steering wheel." In practice, the post 13 is provided at its top with a stud 15 rotatably mounted upon which is the wheel 14, a screw 16 and cap 17 of tin or the like serving to 85 secure the wheel with respect to the post. Upon the front of the steering post is a part symbolic of a cranking device. The latter is shown as comprising a metallic member, preferably wire, bent to form a crank 18 90 rotatable with respect to said post and having secured thereto so as to rotate therewith a metallic disk 19, the peripheral edge of which is serrated or notched as shown in Fig. 4. Secured to the front of the post 13 95 is a spring-metal detent 20 which is in engagement with the serrated edge of said disk 19. Upon turning the crank 18, a sound is produced which in effect is symbolic of the cranking of an engine in so far as the mind 100 of a child is concerned. The rear part 11 embraces an axle 21 provided with journals 22 upon which are mounted wheels 23. In practice, the wheels are maintained in proper position with respect to the journals by 105 means of metallic caps 24 preferably tin and screws 25. At least one wheel has fixed to its inner face a ring-like member 27 of metal, as tin, the outer face of which is crimped or corrugated as at 27'. Fixed preferably to 110 the underside of the axle, so as to be hidden from view as much as possible is a spring-

metal detent 28 which is in engagement with the crimped surface of said ringlike member 27. Rotation of the said wheel produces a sound symbolic of the exhaust of an internal combustion engine in so far as the imagination of a child is concerned. The intermediate part 12 of the toy consists of an elongated member preferably of rectangular cross-section and which member a child 10 straddles with the feet upon the ground when using the toy. In practice, the toy which is constructed to sell very cheaply may be painted in bright colors and the wheels which are disk-like in structure may 15 have delineated thereon representations of tires and spokes and the steering wheel may also have delineated thereon representations of spokes. The spokes in both instances radiate from the caps at the wheel centers which 20 produces a realistic effect. Such a toy, to a child of tender age, is symbolic of an automobile and is a source of harmless amusement.

In Figs. 6 and 7, there is disclosed another form of the same toy which may be used by a child who has outgrown the use of the type above described. In addition to the features above described, use is made of a third or front wheel connected with the 25 steering wheel whereby the toy may be guided and a seat is provided for the comfort of the user. At the front of the toy a pair of standards 30 are employed to form the steering post to which are connected the 30 body part 12. Extended between that part of the body which is secured to the axle 21 and the lower ends of the standards 30 are braces 31 and between the standards at the bottoms thereof is a block 32. This block 35 and that part of the body 12 located between the standards are apertured for the passage therethrough of a spindle 33 the upper end of which is squared and has fixed thereto the steering wheel and the lower end 40 of which is forked for the reception of a wheel 34. The body 12 has secured to the top thereof a seat 35 preferably of wood. Pivoted to the steering wheel 14 is a member 36 symbolic of a spark lever. Otherwise 45 the construction is the same as above set forth with respect to Figs. 1 to 5.

It will now be apparent that I have devised a novel and useful construction which embodies the features of advantage enumerated as desirable in the statement of the invention and the above description and while I have in the present instance shown and described the preferred embodiment thereof which has been found in practice to 55 give satisfactory and reliable results, it is to be understood that the same is susceptible of modification in various particulars without departing from the spirit or scope of the invention or sacrificing any of its advantages.

What I claim is:

1. A toy of the character stated comprising a beam symbolic of an automobile body, a member symbolic of a steering post fixed with respect to one end of said beam, said member being provided with a journal, an axle fixed with respect to the other end of said beam having journals at the respective ends thereof, a disk symbolic of a steering wheel mounted upon the steering post journal, a disk symbolic of an automobile wheel mounted upon each journal of said axle and means for rotatably connecting said disks with respect to said journals. 70

2. A toy of the character recited embracing a rail or beam adapted in use to be straddled by the user with the feet upon the ground, said rail or beam being provided at its forward end with a post equipped with a wheel symbolic of a steering wheel and 85 provided at its rear end with an axle equipped with disks symbolic of automobile wheels and means mounted upon said post for producing sound symbolic of the cranking of an internal combustion engine. 90

3. A toy of the character recited embracing a rail or beam adapted in use to be straddled by the user with the feet upon the ground, said rail or beam being provided at its forward end with a post equipped with 95 a disk symbolic of a steering wheel and provided at its rear end with an axle equipped with disks symbolic of automobile wheels, and means interposed between said axle and wheels for producing a sound symbolic of the 100 "exhaust" of an internal combustion engine.

4. A toy of the character stated comprising means symbolic of an automobile body provided at one end with a device symbolic of a steering wheel and provided at its other 105 end with elements symbolic of automobile wheels, means for producing sound symbolic of the cranking of an internal combustion engine and means for producing sound symbolic of the "exhaust" thereof. 110

5. A toy of the character recited embracing a rail or beam adapted in use to be straddled by the user with the feet upon the ground, said rail or beam being provided at its forward end with a post and provided 115 at its rear end with an axle equipped with disks symbolic of automobile wheels and a spindle passing through said post equipped with a disk symbolic of an automobile wheel at its lower end and equipped with a steering wheel at its upper end and means located upon said post for producing a sound symbolic of the cranking of an internal combustion engine. 120

6. A toy of the character recited embracing a rail or beam adapted in use to be straddled by the user with the feet upon the ground, said rail or beam being provided at its forward end with a post and provided at its rear end with an axle equipped 125

with disks symbolic of automobile wheels and a spindle passing through said post equipped with a disk symbolic of an automobile wheel at its lower end and equipped with a steering wheel at its upper end and means interposed between said axle and rear wheels for producing a sound symbolic of the "exhaust" of an internal combustion engine.

10 7. A toy of the character stated comprising means symbolic of an automobile body provided at one end with a steering column and at its other end with an axle, a steering post for said column provided with elements symbolic of a steering wheel and an automobile wheel, elements symbolic of automobile wheels for said axle, means for producing sound symbolic of the cranking of an internal combustion engine and means for producing sound symbolic of the "exhaust" thereof.

8. A toy comprising a beam adapted in

use to be straddled by the user with the feet upon the ground, said beam being provided at one end with a device symbolic of a steering wheel and provided at its other end with elements symbolic of automobile wheels and means for producing sound symbolic of the "cranking" of an internal combustion engine.

25

9. A toy comprising a beam adapted in use to be straddled by the user with the feet upon the ground, said beam being provided at one end with a device symbolic of a steering wheel and provided at its other end with elements symbolic of automobile wheels and means for producing sound symbolic of the "exhaust" of an internal combustion engine.

30

In testimony whereof, I have hereunto signed my name, in the presence of,

E. S. FOLJAMBE.
